Primary Examiner — Wan Laymon*Assistant Examiner* — Clint A Samuel(74) *Attorney, Agent, or Firm* — Scott T. Griggs; Griggs Bergen LLP(57) **CLAIM**

The ornamental design for a cellular phone accessory package, as shown and described.

DESCRIPTION

FIG. 1 is a front perspective view of a cellular phone accessory package;

FIG. 2 is an additional front perspective view of the cellular phone accessory package shown in FIG. 1;

FIG. 3 is a top plan view of the cellular phone accessory package, with the transparent top shown in FIG. 1 removed for ease of full illustration;

FIG. 4 is a front elevation view of the cellular phone accessory, with the transparent top shown in FIG. 1 removed for ease of illustration;

FIG. 5 is a left side elevation view of the cellular phone accessory, with the transparent top shown in FIG. 1 removed for ease of illustration, which includes left-right symmetry; and,

FIG. 6 is a rear elevation view of the cellular phone accessory package, with the transparent top shown in FIG. 1 removed for ease of illustration.

The dashed and dotted lines shown are provided for environmental purposes only and form no part of the claimed design.

1 Claim, 3 Drawing Sheets(56)
